DOWEL INSERTING DEVICE FOR TIE PINNING MACHINES

Philip de Anguera, Cincinnati, Ohio, assignor to Graham Tie Dowel Service Company, Columbus, Ohio, a corporation of Ohio

Application May 28, 1952, Serial No. 290,526

6 Claims. (Cl. 144—31)

My invention relates to a new and improved spiral dowel inserting device for railroad tie and timber pinning machines. While the invention is particularly directed to a device useful in conjunction with a tie pinning machine, the invention may be applied to other types of machines which require automatic placement of fastener parts for assembly in a work piece.

One of the objects of my invention is to provide at low cost a greatly simplified and dependable dowel inserting device for tie pinning machines, or the like.

Another object of the invention is to provide a practical device which will positively deliver a set of metal spiral dowels from a magazine to a driving position adjacent a tie and force said set into more effective placement in a tie or timber with less expenditure of power.

A further object of the present invention is to provide coordinated mechanisms for feeding metal spiral dowels individual from a stack of dowels disposed in sidewise abutment within a magazine, and for alternately introducing said dowels into each of a pair of delivery chutes which direct them into individual holders in position for axial driving movement into the clamped end of a railroad tie, timber, or the like. The mechanism according to the illustrated embodiment of the invention includes an oscillating dowel distributor disposed beneath a stack of dowels and operating in opposite lateral directions to feed a dowel sidewise first into one and then the other of a pair of chutes positioned on opposite sides and beneath the distributor for delivery therefrom into the individual dowel holders.

Another advantageous feature of this invention resides in the novel cooperation of means employed for holding and forcing a metal spiral dowel into a railroad tie, or a timber, said holding means being characterized by the relatively loose or free fit of the spiral dowel in the holder whilst the push rod for forcing the dowel from the holder into the tie is free to rotate with the dowel as the dowel is driven into the tie or timber.

With these objects in view, the present invention consists in certain features of novelty in the construction, combination and arrangement of parts by which the said objects and certain other objects are effected, all as fully described with respect to the accompanying drawings, and more particularly pointed out in the appended claims.

Reference is hereby made to the accompanying drawings in the several figures of which similar reference numeral designate similar elements and wherein:

Fig. 1 is a cross sectional view taken through the longitudinal center of a machine for inserting spiral dowels in railroad ties.

Fig. 2 is an enlarged section taken on line 2—2 of Fig. 1.

Fig. 3 is a fragmental, side elevational view of the spiral dowel magazine for the machine.

Fig. 4 is an enlarged top plan view of the dowel distributor for the machine.

Fig. 5 is a section taken on line 5—5 of Fig. 4.

2

Fig. 6 is a fragmental section taken on line 6—6 of Fig. 5.

My spiral dowel inserting device is particularly useful in connection with a machine such as that disclosed in my co-pending patent application for Tie Pinning Machine and Method, filed May 11, 1949, and given Serial Number 92,588, now Patent No. 2,636,525. The elements of this tie pinning machine are generally shown in Fig. 1 wherein the numeral 10 indicates a main frame comprising two laterally spaced I-beams 11 and 12 connected together across their opposite ends by cross plates 13 and 14. This frame supports a fixed jaw member 15, and a reciprocated jaw member 16, the latter being movable toward and away from the fixed jaw to respectively clamp and release the end of a railroad tie 17 into which a pair of metal spiral dowels is to be inserted, while the tie is held in compression between the jaws. The movable jaw 16 is operated by a fluid actuated cylinder-piston motor 18 mounted on an upright rear plate 19 of the frame, said motor having a yoke 20 connected to its piston part which in turn is joined to the movable jaw by a pair of longitudinal pull rods 21—22.

Metal spiral dowels such as the one shown at A in Fig. 2 are driven into pre-drilled holes in the tie end held under compression by the jaws by means of two coordinated instrumentalities identified in Fig. 1 of the drawings as a tie drilling device 23 and a dowel inserting device 24. With respect to the drilling device the numeral 25 refers to a drag plate movable upon the frame and coupled to the movable jaw at 26. The drag plate has mounted thereon a drill spindle carriage 27 which has longitudinal reciprocating movement thereon independent of the movement of the plate, said carriage being mounted for rolling movement upon a pair of laterally spaced tracks 28 positioned upon the drag plate adjacent the movable jaw 16. The carriage has a pair of vertically spaced drill spindles 29—29 mounted thereon for vertical adjustment, the drills being continuously actuated during operation of the machine by a suitable motor (not shown). When the tie is held under compression between the jaws 15 and 16 the drills 29 are fed through the movable jaw 16 and through the tie end 17 by means of a fluid actuated, cylinder-piston motor 30 fixed beneath the drag plate 25 and having an operative connection 31 with the underside of the carriage 23, a complete cycle of said carriage comprising the feed stroke wherein the drills are fed entirely through the railroad tie and return movement of the carriage to its inoperative position shown in Fig. 1.

A pair of dowels are next driven into the pre-drilled holes formed in the tie while it remains under compression by a mechanism generally indicated by the reference numeral 24, said mechanism comprising a pair of vertically spaced, hollow dowel holders 32—33 disposed rearwardly of the fixed jaw member 15 and operative therethrough, said holders being vertically adjustable so that they are susceptible of axial alignment with the drill spindles 29. Each of the dowel holders has a freely rotatable pusher rod 34—35, respectively, operable therethrough to axially drive a dowel from the holder into the pre-drilled hole in the tie, said pusher rods being simultaneously driven by a fluid actuated cylinder-piston motor 36 mounted on the plate 19 and connected to the rods by a cross head 37.

As most clearly shown in Fig. 6 the cross head 37 has a channel shaped frame 38 comprising two opposed side walls 39, a back wall 40 and opposed end walls 41. The side walls each have a guide 42 extending inwardly therefrom which engage slots 43 formed in the opposed side walls of a pair of vertically movable blocks 44, said blocks each being held in vertically adjusted positions by means of set bolts 45 which are threaded in the blocks and pass

through elongated slots 46 formed in the side walls 39. Each push rod 34-35 is provided with a reduced end 47 which is journalled in a bore 48 formed through a block 44, said bore having an enlarged forward end 49 for housing an anti-friction thrust bearing unit 50. The end of the push rod is threaded at 51 to cooperate with a pair of lock nuts 52 to preclude axial displacement of the push rods when they are retracted toward their inoperative positions illustrated in Fig. 1.

Turning now to my novel dowel feeding and driving device it will be noted with reference to Figs. 3 and 4 that the holders 32 and 33 extend longitudinally of the machine and are normal to the fixed jaw member 15, said jaw having formed therethrough a pair of vertically spaced slots 53-53 through which the holders direct driven spiral dowels into the clamped tie end 17. The holders are mounted behind the fixed jaw 15 by means of a bearing plate 54 welded to the jaw and supported upon a frame member 55 by two longitudinally spaced gusset plates 56 and 57 (Figs. 4 and 5). The holders are identical in construction and a description of one holder will suffice for a clear understanding of both. Each holder has an elongated, solid block 58 formed with a centrally located slot 59 through which a vertical adjusting screw 60 passes, said screw being journalled at its ends in lateral extensions 61 and 62 of the bearing plate 54. The screw has right and left externally threaded portions 63 and 64 which cooperate with nuts 65 and 66 that are held against rotation in routs milled in the blocks of the holders 32 and 33, rotation of the screw being adapted to vertically adjust the holders so that they are brought into axial alignment with the drill spindles 29 and with the through holes formed by the said drills in the tie end 17. The blocks are guided for vertical movement by a pair of tracks 67-67 mounted on the interior face of the bearing plate 54 and receivable in a pair of vertical guide slots 68-68 formed in each of the blocks 58.

As best shown in Figs. 5 and 6 each holder has a longitudinally extending, semi-cylindrical slot 69 formed in a side thereof into which is fitted a thick walled tube 70, said tube being preferably sectionized to the end that the front section 71 thereof encloses a wear resistant liner 72 of high carbon steel whilst the upper portion of the wall of a rear section 73 is provided with a longitudinal slot 74 through which a metal spiral dowel A falls by gravity into driving position within a through-opening or bore 75 in the tube. End blocks 158 and 159 are welded to the outer lateral face of the block 58 to keep the holder assembly together, it being seen with reference to Fig. 4 that a holder retaining slide 160 is fixed to the outer face of the jaw 15 for cooperation with slide ways 161 formed in the end block 158.

With reference to Fig. 6 it is to be noted that the terminal end of the rotatable push rod 35 is entered in the rearward end of the through-opening 75 in the holder and beyond the slot 74 when in inoperative position, said rod end being adapted upon actuation of the rod to engage the trailing end of the spiral dowel and push it axially through the opening 75 and into a pre-drilled hole 76 formed in the timber end 17. It will be further observed with reference to Fig. 6 that the diameter of the through-opening 75 in the tube 70 is substantially greater than the outside diameter of the spiral dowel which results in a loose or free fit of the dowel in its holder, and that the working face 77 of the push rod is concave or cup shaped. The loose fit of the dowel in the tube permits the leading end of the dowel sufficient lateral movement when it is pushed into the tie end that it will seek and find the mouth of the pre-drilled hole which may not be in axial alignment with the holder due to occasional lateral wander of the drills through certain wood conditions in a particular tie. The concave, working end of the rod provides adjustment of the trailing end of the dowel to compensate for lateral adjustment of its leading

end so that the dowel may remain clear of the interior surface of the holder as it is driven into the timber. Enlargement of the inside diameter of the dowel receiving tubes with respect to the outside diameter of the dowels permits the holders to accommodate and successfully drive dowels which may be imperceptibly curved along their longitudinal axes whilst such difference facilitates self-cleaning of the holder tube of chips and foreign matter by movement of the push rods therethrough.

10 The diameter of the pre-drilled holes 76 in the tie or timber 17 are the root diameter of the dowels such that the dowels upon being forced thereto rotate and cut interior threads into the drilled holes. Rotation of the push rods precludes dowel binding and freezing on the working surface of the push rods 34-35, insures the cutting of accurate, distinct threads by the dowels in the pre-drilled holes in the tie and greatly reduces the power needed to push said dowels into the pre-drilled holes in the tie.

15 20 A rotary dowel distributor 78 is positioned above the levels of the dowel holders 32 and 33 and beneath a dowel feed chute 79 which feeds dowels by gravity to the distributor from a hopper 80. As shown in Figs. 1 and 2 the hopper is supported on legs resting upon the machine frame and has a pair of vertical end walls 81-81 and downwardly converging side walls 82 and 83. The side wall 83 is formed by a series of laterally spaced bars 84 (Figs. 2 and 3) which are inclined downwardly to the mouth of the hopper where they are bent and extended 25 30 vertically downwardly to the distributor 78, said vertical portions of the bars forming one side wall 85 for the dowel feed chute 79. Interposed between the inclined portions of the bars 84 are a series of dowel agitating rocker bars 86 pivoted on a common pivot rod 87 that 35 extends through and is anchored in the bars 84. The agitating bars are secured together at their upper ends on a connecting shaft 88 whilst their opposed free ends (Fig. 2) form a vibrating single file passageway for the dowels as they pass into the top of the feed chute from the hopper 80, there being indicated at 89 a side wall of spaced vertical bars which cooperate with the side wall 85 to form a feed chute passageway 90 for supporting a vertical stack of spiral dowels in side-to-side relationship. A dowel distributing rotor 91 is positioned directly beneath the stack of dowels in the feed chute 79 and has formed in its side wall two spaced dowel receiving pockets in the form of longitudinal grooves 92 and 93, said rotor being mounted between two bearing blocks 94 and 95 each bolted to the upper portion of the bearing plate 54.

40 50 The means for oscillating the rotor comprises an arm 96 fixed to the rotor shaft and which in turn is connected to a rocker arm assembly 97 by a link 98. As best shown in Figs. 4 and 5, the rocker arm assembly comprises a pair of plates 99 and 100 held in face-to-face relationship by a pair of contractile springs 101 and 102. Common ends of these springs are connected to opposed arms 103 on a plate 104 welded to and extending at right angles from the plate 99, while the opposite ends of the springs are secured to a pair of arms 105 carried on a plate 106 secured at right angles to the plate 100. The free end of plate 104 is pivotally connected to the depending end of the link 98. The plates are held in alignment and are rockable on opposed separable hinge knuckles 107 to provide a jointed rocker arm normally spring held in extended, operative position but laterally yieldable under excessive pressure to act as a safety device for the prevention of damage to machine parts. Plate 100 also has two spaced arms 108 secured to its face, said arms being pivotally mounted at 109 to a bracket 110 bolted to a frame member 155. An intermediate portion of the arms are connected by a loose link 111 to the connecting rod 112 of a fluid actuated cylinder-piston motor 113 positioned upon said frame member 155. The outer ends of the arms 108 are pivotally connected to a sleeve 117 which 55 60 65 70 75 telescopically receives the lower end of a rod 114 threaded

at its upper end in a tapped bore 116 formed in a coupler 115 which in turn is loose on the connecting rod 88 for the agitating bars 86 of the hopper 80. Adjustment of the coupler and the rod is maintained by a set nut 118 threaded on the rod and engaged against the depending end of the coupler, the telescopic connection between the sleeve and the rod being held together by means of a pair of contractile springs 119 hooked over the connecting shaft 88 and secured to the pivot connection 120 between the arms 108 and the shaft 114.

It will therefore be understood that under normal operating conditions actuation of the motor 113 will cause the assembly 97 to rock on its fulcrum 109 thus oscillating the rotor 91 to cause it to feed a dowel from the bottom of the stack in feed chute 79 into one and then into the other of the dowel holders 32 and 33. Rocking of the assembly 97 also moves the sleeve 117 and rod 114 upwardly which rocks the dowel agitating bars 86 to insure a flow of dowels to the mouth of the hopper and to preclude jamming of the dowels as they enter the dowel feed chute 79. In the event the rotor should become frozen or jammed for any reason, the assembly will flex back and forth so that the motor 113 may continue to rock the arms 108 whilst plate 104 is stationary, because the plates 99 and 100, to which the plate 104 and the arms 108 are respectively connected, can rock from one and then to the other of the separable sockets 107 against the action of the springs 101 and 102 which have enough tension to hold plates 99 and 100 in face-to-face relation for normal operation of the rotor but are extensible under undue tension. Likewise when dowels become jammed under the terminal ends of the bars 86 the telescopic connection between sleeve 117 and rod 114 will be extensible against the action of the springs 119 thus precluding damage to the machine parts.

The machine is provided with a suitable fluid pressure system and controls (not shown) which successively introduces pressure fluid into motor 18 to clamp the end of a tie 17 between the jaws 15—16, then to operate motor 30 to feed and return the drills 29 from pre-drilled holes in the timber end, and then actuate cylinder 36 to operate the push rods 34—35 to drive dowels from the holders into the pre-drilled holes in the timber end, it being contemplated that the motor 113 should complete one cycle during the tie clamping operation to thereby rock the arm 108 and oscillate both the rotor 91 and the dowel agitator bars 86 of the hopper.

As depicted in Fig. 5 oscillating movement of the rotor comprises first rotating the rotor 91 counterclockwise to move the lowermost dowel sidewise from beneath the stack into a position where it will fall from the slot into the guide chute 121 and down into the slot 74 in the holder 32, said counterclockwise movement of the rotor also bringing the slot 92 beneath the stack of pins in the feed chute to receive the lowermost dowel therein. Clockwise movement of the rotor as seen in Fig. 5 then carries the dowel in slot 92 to a position where it is dropped from slot 92 into guide chute 122 and thence into the holder 32, this movement also returning the slot 93 in the rotor beneath the stack of dowels in position for the next dowel feeding operation.

What is claimed is:

1. A device for driving spiral dowels into a tie comprising a pair of horizontal dowel holders fixedly positioned adjacent a portion of the timber to be dowelled, each of said holders having an upwardly opening through-slot therein, and said holders being positioned on different levels, an upstanding guide chute communicating with each through-slot, a feed chute located above the holders for holding a stack of dowels therein in side-to-side relationship, a rotor mounted for rotation beneath the discharge end of the feed chute, said rotor being formed with a first and a second angularly spaced apart, dowel receiving pocket, means for oscillating the rotor from a first position to a second position and return, whereby in

said first position of the rotor the first pocket is located directly beneath the discharge end of the feed chute to receive a dowel and in the second rotor position the said dowel is delivered out of said pocket into one guide chute and its associated holder whilst the second pocket is in dowel receiving position beneath the discharge end of the feed chute and return movement of the rotor discharges the dowel in the second pocket into the remaining guide chute and its associated holder as the first pocket is returned to the first rotor position, and means for driving the dowels deposited in the holders axially into the tie.

2. In a device for driving a spiral dowel into a pre-drilled hole formed in a tie comprising a frame, a clamp on the frame for holding the pre-drilled portion of the timber, a hollow dowel holder positioned on the frame to position a dowel therein in longitudinal alignment with the hole in the timber, a pusher rod movable through the holder and having a cupped end for receiving the end of a spiral dowel therein, a reciprocating motor mounted on the frame, and an anti-friction drive connection between the motor and the rod to permit free rotation of the rod around its longitudinal axis as it forces a spiral dowel out of the holder and into the pre-drilled hole in the tie.

3. In a device for driving a spiral dowel having a pointed pilot end into pre-drilled holes formed in a tie comprising a frame, a fixed jaw member and a relatively movable jaw member mounted on the frame for clamping the drilled portion of the tie therebetween, a dowel holder carried by the fixed jaw member and having an open topped cylindrical bore formed therethrough, and disposed in axial alignment with the hole in the timber held between the jaw members, said bore having an oversize inside diameter with respect to the outside diameter of the spiral dowel receivable therein, a rotatable, cylindrical pusher rod movable through the bore and having a concave dowel engaging face on its inner end, a reciprocating motor mounted on the frame, and an anti-friction connection between the motor and the outer end of the rod to permit rotation of the pusher rod around its longitudinal axis as it forces a spiral dowel out of the bore and into the pre-drilled hole in the tie.

4. In a device for driving a spiral dowel into each of a pair of pre-drilled holes formed in a tie comprising a frame, a fixed jaw member and a relatively movable jaw member mounted on the frame for clamping the tie therebetween, a pair of dowel holders mounted on the fixed jaw member in axial alignment with the pre-drilled holes in the timber, a push rod mounted for sliding movement in each of the holders, intermittent power means for operating the push rods, a dowel feed chute mounted on the frame above the holders, a rotary dowel distributor mounted on the frame directly beneath the discharge end of the feed chute and above the holders, means for oscillating the distributor to successively feed the lowermost dowel in the feed chute into one and then into the other of the dowel holders, said means comprising a rock arm mounted on the frame, an operating arm fixed to the rotor, and a link connection between one end of the rock arm and the said operating arm, a dowel hopper supported on the frame and including a bottom portion having a spaced series of bars inclined downwardly to the mouth of the feed chute, dowel agitating bars interposed between the inclined bars and rockably mounted therebetween, a connecting rod between the outer ends of the agitating bars and the rock arm, and a reciprocating motor for intermittently actuating the rock arm during dwell periods of the push rods.

5. In a device according to claim 4 characterized by the fact that the rock arm is laterally yieldable under excessive operating conditions of the rotor.

6. In a device according to claim 5 further characterized by the fact that the connecting rod between the dowel agitating bars and the rock arm is yieldable under excessive operating conditions of the agitating bars.
